RAILWAY TRACK STRUCTURE

William Dalton, Schenectady, N. Y.

Application December 5, 1932, Serial No. 645,657

7 Claims. (Cl. 238—349)

My invention more particularly relates to a track structure comprising a rail fastener which is simple in construction and easy to make and which at the same time exerts a sufficient amount 5 of pressure on the rail to securely hold the same on the supporting structure and prevent creeping thereof, thereby avoiding the use of special anti-creeping devices.

Other objects of my invention will appear in 10 the specification and will be more particularly pointed out in the claims.

My invention will best be understood by reference to the accompanying drawings in which I have illustrated certain embodiments thereof 15 and in which—

Fig. 1 is a fragmentary perspective view of a rail structure embodying my invention;

Fig. 2 is a plan view thereof;

Fig. 3 is a sectional view taken along the line 20 3—3 of Fig. 2;

Fig. 4 is a plan view illustrating a modified form of rail fastener;

Fig. 5 is a section taken along the line 5—5 of Fig. 4;

Fig. 6 is a side view of a modified form of rail fastener; and

Fig. 7 is a side view of a further modified form of rail fastener.

Like reference characters indicate like parts 30 throughout the drawings.

Referring to the drawings, and first to Figs. 1, 2 and 3, 10 is a railway tie here illustrated as formed of wood, though it will be understood that my invention is equally applicable to a track having 35 metal ties. A tie plate 11 is secured to the tie by the usual bolts 12. In the embodiment of my invention illustrated in Figs. 1, 2 and 3 the tie plate 11 is provided with double lips 13 forming a recess 14 in which is seated the flange 151 40 of a track rail 15. The lips 13 prevent lateral movement of the rail 15.

The rail is secured to the tie plate by a rail fastener indicated generally at 16 and comprising a piece of spring metal bent to form a loop 17 the 45 major portion of which is curved in the same direction to form a convex surface on the outside. While I prefer to curve the entire loop in the same direction and have so illustrated the same, it will, of course, be understood that the advantages of 50 my invention could be secured if the loop were not curved in the same direction throughout.

One end of the fastener is shaped to form a shoulder 18 which normally engages the outer wall of an opening 20 with which the tie plate 55 is provided thereby retaining the fastener in op-

erative position by preventing lateral displacement thereof. The extreme end of the fastener is preferably beveled as at 19 from the shoulder to the end of the fastener. The tie plate is also preferably provided with a recess 21 formed on 60 the lower side thereof adjacent to said opening and on the wall of the opening opposite that which is engaged by the shoulder 18. In the embodiment of my invention illustrated in Figs. 1, 2 and 3, the shoulder 18 is formed by forging 65 the metal at the end of the fastener so that the shoulder is formed integrally with the main body thereof and the opposite end 161 of the fastener engages the upper side of flange 151 of the rail preferably adjacent to the opening 20. 70

In the embodiment of my invention illustrated in Figs. 1, 2 and 3, one end of the fastener is preferably made straight from the point *a* to the end which engages the rail flange and the inner side of the opposite end is also made 75 straight from the point *b* to the end which is received in the recess 21.

To insert the fastener in position, one end thereof is placed in engagement with the flange of the rail, and the opposite beveled portion thereof is inserted in the opening 20 with the beveled portion thereof engaging the edge of the outer wall of the tie plate around the opening. Then by delivering a sharp blow to the fastener by a suitable tool, the shoulder 18 rides over the edge 85 of the outer wall surrounding the opening and snaps into position with the shoulder engaging the outer wall in the position illustrated in Fig. 3 and the end thereof received in the recess 21.

In the embodiment of my invention illustrated 90 in Figs. 4 and 5 the fastener is curved to the outer end thereof, and the end of the fastener instead of engaging the upper surface of the flange as in Fig. 3, engages the edge of the flange so that it prevents not only the upward movement of the 95 rail but the lateral movement thereof which is, of course, a particularly valuable feature where the tie plate is not provided with lips to prevent lateral displacement of the rail.

In the embodiment of my invention illustrated 100 in Fig. 6, the inner end of the fastener 16a is slightly offset as at 22 to form the shoulder 18a.

In the embodiment of my invention illustrated 105 in Fig. 7, a separate piece of metal 23 is secured to the outer side of the fastener 16b adjacent one end thereof, the same preferably being spot welded thereto as at 24. The piece 23 is preferably beveled as at 25 to permit easy insertion 110 of the fastener in position.

By curving the major portion of the loop of the fastener in the same direction in the manner illustrated, the loop is formed on a comparatively large radius of curvature with the result that the 5 fastener may be made of larger cross sectional area than would be the case if the loop were formed with reverse curves and with comparatively small radii of curvatures and may be made heavy enough to exert sufficient pressure on the 10 rail to prevent its being either vertically or longitudinally displaced.

While I have described my invention in its preferred embodiments, it will be understood that the words which I have used are words of description rather than of limitation and that changes within the purview of the appended 15 claims may be made without departing from the true scope and spirit of my invention in its broader aspects.

20 What I claim is:

1. In combination, a metallic supporting structure provided with an opening and with a recess on the under side of said structure adjacent the inner wall of said opening, a track rail mounted 25 on said supporting structure, and a track fastener comprising a piece of spring metal bent to form a loop, one end of said fastener being received within said recess and an adjacent portion of said end being provided on its lower side with a shoulder 30 engaging the outer portion of the wall surrounding said opening, another portion of said fastener engaging a flange of said rail in a position to exert a downward pressure thereon.

2. In combination, a metallic supporting structure provided with an opening and with a recess 35 on the under side of said structure adjacent the inner wall of said opening, a track rail mounted on said supporting structure, and a track fastener comprising a piece of spring metal bent to form 40 a loop, one end of said fastener being received within said recess and an adjacent portion of said end being provided on its lower side with a shoulder 45 engaging the outer portion of the wall surrounding said opening, another portion of said fastener engaging a flange of said rail in a position to exert a downward pressure thereon, the major portion of said loop being included between said shoulder and the rail engaging portion of the fastener.

50 3. In combination, a metallic supporting structure provided with an opening and with a recess on the under side of said structure adjacent the inner wall of said opening, a track rail mounted 55 on said supporting structure, a track fastener comprising a piece of spring metal bent to form a loop, one end of said fastener being provided with a shoulder adapted to engage the upper edge of the outer wall surrounding said opening and to 60 extend diagonally downwardly and inwardly across said opening and receivable within said

recess, another portion of said fastener engaging a flange of said rail in a position to exert a downward pressure thereon.

4. In combination, a metallic supporting structure provided with an opening and with a recess 80 on the under side of said supporting structure adjacent the inner wall of said opening, a track rail mounted on said supporting structure and a track fastener comprising a piece of spring metal bent to form a loop, one end of said fastener being wedge-shaped and received within 85 said recess and an adjacent portion of said end being provided on its lower side with a shoulder engaging the outer portion of the wall surrounding said opening, another portion of said fastener engaging a flange of said rail in a position to exert a downward pressure thereon.

5. In combination, a metallic supporting structure provided with an opening and with a recess 90 on the under side of said structure adjacent the inner wall of said opening, a track rail mounted on said supporting structure and a track fastener comprising a piece of spring metal bent to form a loop, one end of said fastener being received within 95 said recess and an adjacent portion of said end being provided with a member welded to the under side of said fastener and forming a shoulder therewith and engaging the outer portion of the wall surrounding said opening, another portion of said fastener engaging a flange of said rail in a position to exert a downward pressure thereon.

6. In combination, a metallic supporting structure provided with an opening and with a recess 100 on the under side of said structure adjacent the inner wall of said opening, a track rail mounted on said supporting structure, and a track fastener comprising a piece of spring metal bent to form a loop, one end of said fastener being received within 105 said recess and an adjacent portion of said end being provided with a member welded to the under side of said fastener and forming a shoulder therewith and engaging the outer portion of the wall surrounding said opening, another portion of said fastener engaging a flange of said rail in a position to exert a downward pressure thereon.

7. In combination, a metallic supporting structure provided with an opening and with a recess 110 on the under side of said structure adjacent the inner wall of said opening, a track rail mounted on said supporting structure, and a track fastener comprising a piece of spring metal bent to form a loop, one end of said fastener being received within 115 said recess and an adjacent portion of said end being provided on its lower side with a shoulder 120 engaging the outer portion of the wall surrounding said opening, the other end of said fastener directly engaging a flange of said rail in a position to exert a downward pressure thereon.

125 7. In combination, a metallic supporting structure provided with an opening and with a recess on the under side of said structure adjacent the inner wall of said opening, a track rail mounted on said supporting structure, and a track fastener comprising a piece of spring metal bent to form a loop, one end of said fastener being received within 130 said recess and an adjacent portion of said end being provided on its lower side with a shoulder 130 engaging the outer portion of the wall surrounding said opening, another portion of said fastener engaging the upper corner of a flange of said rail to exert a downward pressure thereon.

WILLIAM DALTON. 135
